DESIGN FOR A FOOD MIXER

George T. Scharfenberg, Chicago, Ill., assignor to Chicago Flexible Shaft Company, Chicago, Ill., a corporation of Illinois

Application July 15, 1939, Serial No. 86,038

Term of patent 14 years

To all whom it may concern:

Be it known that I, George T. Scharfenberg, a citizen of the United States, residing at Chicago, in the county of Cook and State of Illinois, have invented a new, original, and ornamental Design for a Food Mixer, of which the following is a specification, reference being had to the accompanying drawing, forming part thereof.

In the drawing:

Fig. 1 is a side view of a food mixer, embodying my new design;

Fig. 2 is a rear end view, and
Fig. 3 is a front end view thereof.

The dominant features of the design reside in the portions shown in full lines.

I claim:

The ornamental design for a food mixer, substantially as shown and described.

GEORGE T. SCHARFENBERG.
